UNITED STATES PATENT OFFICE.

ROBERT WHITEHILL, OF MILWAUKEE, WISCONSIN.

DUST-COLLECTOR.

SPECIFICATION forming part of Letters Patent No. 360,129, dated March 29, 1887.

Application filed January 21, 1886. Serial No. 189,266. (No model.)

To all whom it may concern:-

Be it known that I, ROBERT WHITEHILL, of Milwaukee, in the county of Milwaukee, and in the State of Wisconsin, have invented 5 certain new and useful Improvements in Dust-Collectors; and I do hereby declare that the following is a full, clear, and exact description thereof.

My invention relates to dust-collectors for 10 flouring-mills; and it consists in certain peculiarities of construction and combination of parts, as will be fully described hereinafter with reference to the accompanying drawings and subsequently claimed.

15 Figure 1 represents a side elevation, partly in section, showing the casing of my dust-collector, a portion of the balloon, driving-gear, and air-discharge nozzle; Fig. 2, an enlarged detail sectional view showing the means for 20 forming an air-tight joint between the draft-flue and balloon-head; Fig. 3, a vertical longitudinal section showing the internal construction of my dust-collector and the operative relation of the several parts composing 25 the same; Fig. 4, an enlarged detail sectional view showing a portion of the balloon, a toothed segment-plate, a portion of the casing, and one of the guides for the annulus that is formed by the segment-plates; and Fig. 5, a vertical 30 section through the fan, with the adjacent end of the main casing removed to show the relative position of the balloon-cloth and brush.

A represents the casing of my dust-collector, which is provided with a removable hood, A'; 35 and B, a central driving-shaft, to which motion is imparted in any suitable manner. One end of the shaft B is worm-geared at a to a vertical shaft, C, which in turn is bevel-geared at b to a horizontal shaft, D, this latter shaft having 40 a sprocket-wheel-and-chain connection, c, with a conveyer, E.

To the horizontal shaft D, near each end and within the casing A, are keyed gear-wheels F, which respectively mesh with an 45 annulus formed by a series of toothed segment-plates, d, bolted or otherwise secured to the outer sides of the solid circular balloon-heads G G', so as to revolve in flanged guides e, secured to the inner sides of the casing A, as 50 illustrated in detail, Fig. 4, and the head G has

a loose bearing on the shaft B, while the gear-wheels F F revolve said heads by engagement with the toothed annuli formed thereon.

To the heads G G' is fastened in any suitable manner the balloon-cloth H, and this cloth is 55 held taut by means of cords f, having their ends united by springs g, the tension of the latter acting to draw said cords and cloth into annular grooves h, formed in the rims of the aforesaid balloon-heads. Suitably secured to 60 one of the outer sides of the casing A is the casing I of a suction-fan, the vanes i of said fan being keyed to the driving-shaft B.

Leading from the center of the balloon to the interior of the fan-casing is a horizontal 65 draft-flue, K, and depending from said fan-casing is a blast-flue, L, adapted to enter the casing A, and provided at its inner end with a tapering nozzle, M, having a minute discharge-opening or mouth, k, designed to come 70 immediately beneath the balloon-cloth H, on a line with the axial center of a transverse brush, N, that is suspended in brackets m, secured to a beam, n, made fast to that portion of the draft-flue K upon the inside of the balloon. Instead of the brush N, I may employ 75 a roller to depress the balloon-cloth, so as to bring the latter directly in the path of the air discharged through the nozzle M.

In order to form an air-tight joint between 80 the draft-flue K and the balloon-head G', through which said flue passes, I employ strips p p', preferably of felt, the strip p on the inner side of the balloon-head being usually plain, while the one p' on the outer side thereof 85 may be folded, and that portion adapted to come against the flue is stuffed with fibrous material to form a roll, p'', this construction being illustrated in detail, Fig. 2. The loose bearing of the balloon-head G is also made 90 air-tight by packing-strips t, which latter may be either plain or stuffed.

The fan-casing I is provided with a discharge-opening, r, that enters the flue L, and at this point I provide a deflector, s, to direct 95 the current down said flue; and to prevent the fan from clogging, I also provide the casing with another discharge-opening, u, to carry off the surplus air.

In the operation of my invention, the driv- 100

ing-shaft B, being set in motion, will, through the medium of the gearing above described, cause the balloon, fan-vanes, and conveyer to revolve. The suction created by the revolution of the fan-vanes draws the dust-laden air in a constant current up the flues *v* and in the direction of the arrows, Fig. 3, through the balloon-cloth H and draft-flue K, into the fan-casing I, leaving the dust to accumulate upon said balloon-cloth, which is stretched tightly on the heads G G', as above described. As the balloon is revolved, the cloth H thereof comes in constant contact with the brush N, which acts to loosen the dust accumulated on said cloth, and a portion of the air drawn into the fan-casing I is forced down the flue L and discharged through the mouth *k* of the nozzle M, immediately below said brush, thus causing the loosened dust to be blown off into the conveyer E, to be carried away.

Having thus fully described my invention, what I claim as new, and desire to secure by Letters Patent, is—

1. In a dust-collector, a main casing, a traveling collecting medium, and a central draft-flue, in combination with a brush hung within said medium and arranged to come in contact with the cloth thereof, a suction-fan, and blast-flue provided with a nozzle having its mouth immediately below the brush and outside of said collecting medium, substantially as described.

2. In a dust-collector, a collecting medium having solid circular heads, each provided with an exterior annulus composed of a series of toothed segment-plates, in combination with flanged guide-plates interiorly secured to the main casing and a revolving transverse shaft carrying gear-wheels that mesh with the respective annuli on said heads, substantially as described.

3. In a dust-collector, a main casing, a traveling collecting medium, and a draft-flue that has its inner terminus in the center of the collecting medium, in combination with a depressor hung within said medium and arranged to come in contact with the cloth thereof, a suction-fan, and a blast-flue provided with a nozzle having its mouth immediately below the depressor and outside of the said collecting medium, substantially as described.

4. In a dust-collector, a main casing and a collecting medium that comprises solid circular heads having annular grooves in their rims, a suitable cloth stretched over the heads, and cords united at their ends by springs and arranged to draw the cloth into said grooves, in combination with means for revolving said medium and means for drawing a current of air through the same, as set forth. 55

5. In a dust-collector, a main casing, a traveling collecting medium, and a central draft-flue, in combination with a suction-fan having its casing provided with a discharge-opening connected with a blast-flue and a deflector arranged to direct the air-current down said flue, a brush hung within the collecting medium and arranged to come in contact with the cloth thereof, and the blast-flue provided with a nozzle having its mouth immediately 65 below the brush outside of said collecting medium, substantially as described.

6. A dust-collector comprising a main casing, a traveling collecting medium, a central draft-flue, a brush suspended within and arranged to come in contact with and depress the cloth of said medium, a suction-fan uniting with said draft-flue, a blast-flue having a tapered nozzle arranged immediately below said medium and brush, and a suitable conveyer, substantially as described. 75

7. A dust-collector comprising a main casing, a traveling collecting medium, a central draft-flue, a brush suspended within and arranged to come in contact with and depress 85 the cloth of said medium, a suction-fan uniting with said draft-flue, a blast-flue having its mouth immediately below the brush and outside said cloth, and strips of felting secured to the heads of the collecting medium to impinge 90 against the central draft-flue and main shaft, as set forth.

In testimony that I claim the foregoing I have hereunto set my hand, at Milwaukee, in the county of Milwaukee and State of Wisconsin, in the presence of two witnesses. 95

ROBERT WHITEHILL.
